(57) **CLAIM**

The ornamental design for a garbage truck toy, as shown and described.

DESCRIPTION

FIG. 1 is a perspective view of garbage truck toy, showing our new design;

FIG. 2 is a bottom perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof;

FIG. 8 is a bottom plan view thereof;

FIG. 9 is an enlarged perspective view of the rear wheel area taken from the broken line circle 9 of FIG. 1;

FIG. 10 is an enlarged perspective view of the front wheel area taken from the broken line circle 10 of FIG. 1;

FIG. 11 is an enlarged perspective view of front area taken from the broken line circle 11 of FIG. 1;

FIG. 12 is an enlarged bottom perspective view of a support area for a refuse container on the rear of the garbage truck toy taken from the broken line circle 12 of FIG. 2;

FIG. 13 is an enlarged bottom perspective view of an access door area on the side of the garbage truck toy taken from the broken line circle 13 of FIG. 2;

FIG. 14 is an enlarged bottom perspective view of a lift arm area of the garbage truck toy taken from the broken line circle 14 of FIG. 2; and,

FIG. 15 is an enlarged bottom perspective view of a portion of a refuse container on the front of the garbage truck toy taken from the broken line circle 15 of FIG. 2.

The dash-dot broken lines are included to annotate partial views in FIGS. 1, 2 and 9-15. All other broken lines

(Continued)

represent portions of the article that form no part of the claimed design. None of the broken lines form a part of the claim.

1 Claim, 15 Drawing Sheets
